COSMETIC HOLDER

Rudolph N. Houlihan, Bridgeport, Conn., assignor
to The Bridgeport Metal Goods Manufacturing
Company, Bridgeport, Conn., a corporation of
Connecticut

Application May 29, 1947, Serial No. 751,240

11 Claims. (Cl. 206—56)

1

This invention relates to cosmetic holders, particularly to the type of holder for a stick of plastic material such, for example, as lipstick and the like. In a common type of cosmetic holder, particularly a lipstick holder, the stick of plastic is mounted in a carrier which is normally enclosed in an outer body shell or casing open at one end, with means operable by relative turning movement between the enclosing shell or casing and a finger grip at the opposite end for projecting the lipstick through the open end of the casing to a position of use, and then retracting it into the casing for protection. When retracted, the open end of the shell or casing is closed by a removable cap or closure telescoped over this shell or casing. A serious objection in the common type of holder is that, when the closure cap or cover is in place the propeller mechanism for shifting the lipstick to the position of use may be operated to advance the stick and jam it against the closed end of the cap or closure. This makes a messy condition within the holder itself, and also mars, deforms or mashes the free end of the stick of plastic itself, and particularly is this objectionable when the device is on display in a store or on a sales counter, as it is very common for a prospective customer to pick up the holder and operate the finger grip in examining the article, with the result that the free end of the plastic stick is jammed, crushed, and forced out of shape, making the article unsalable.

It is, therefore, a principal object of the present invention to provide a simple and novel construction for this type of device, whereby, when the closure cap or cover is in place over the open end of the shell or casing it is impossible to operate the propeller mechanism to feed the plastic from the enclosing shell or casing and jam it against the closed end of the cover or closure.

Another object is to provide a construction for securing the cover or closure in position on the shell or casing, in which, although the closure is retained in the closing position, it has a free turning movement with respect to the enclosing shell or casing and the finger grip or operating head, so that it is impossible while the closure is in place to cause relative movement between the shell or casing and the operating head or finger grip to propel the stick of plastic from the shell or casing and jam it against the closure.

A further object is to provide an improved and simplified means of so securing the cover or closure cap in place.

2

With the foregoing and other objects in view, I have devised the construction illustrated in the accompanying drawing, forming a part of this specification. It is, however, to be understood the invention is not limited to the specific details of construction and arrangement shown, but may embody various changes and modifications within the scope of the invention.

In this drawing:

10 Fig. 1 is a partial side elevation and partial longitudinal section of a lipstick holder on an enlarged scale, showing a construction embodying my invention;

15 Fig. 2 is a side elevation of the inner rotating sleeve or body and on a smaller scale;

Fig. 3 is a side elevation of the stationary operating sleeve;

Fig. 4 is a side elevation of the outer body shell or casing, and

20 Figs. 5, 6, 7 and 8 are sections of the lower end portion similar to the lower portion of the section of Fig. 1, showing respectively different modifications of the device.

25 Referring first to Fig. 1, the holder comprises an outer body shell or casing 10 open at its opposite ends and enclosing a carrier 11 for a stick of plastic cosmetic material such, for example, as lipstick or the like, the carrier and the stick being slidably longitudinally within the body shell or casing. The means for effecting 30 this longitudinal shifting movement of the carrier and the stick to project the stick through the open end of the shell for use or retract it into the shell for protection when not in use, comprises an inner rotary sleeve 13 open at its upper end, and it may be either open or closed at its lower end, and it is provided with a pair of longitudinally spaced outwardly extending circumferential shoulders preferably formed by beads 14 and 15. The bead or shoulder 14 is 35 located adjacent the open upper end of the sleeve while the lower bead or shoulder 15 may be placed at different positions, as found desirable, but is preferably located as low as possible on the tube to permit the use of a longer intermediate or stationary tube or sleeve 16 to 40 secure greater travel for the carrier 11 and the plastic stick 12. This intermediate or stationary sleeve 16 may be rolled up from a strip of sheet metal with the opposed end edges somewhat spaced, as indicated at 17, to provide a longitudinally slit sleeve, and it is provided with a spiral or inclined slot 18. If the sleeve is a slit sleeve as shown, this spiral slot terminates a short distance from the ends of the sleeve, 45 but a somewhat modified type of sleeve is also

50 55

commonly used for the same purpose in which the spiral slot extends through the ends of the sleeve. As this latter construction permits expansion and contraction of the sleeve it is not necessary to employ the longitudinal slot 17. The sleeve 16 is placed on the inner sleeve 13 and is held thereon by the beads 14 and 15 against relative longitudinal movement, and then this assembly is inserted in the outer body shell 10. Sleeve 16 is made normally of somewhat larger diameter than the interior diameter of the member 10 so that it is compressed somewhat when inserting it in this outer member, and then, by its resilient or spring action it expands against the member 10 to engage this member with sufficient friction to retain the sleeves 13 and 16 in the operating position within the member 10. The carrier 11 is provided with a laterally extending projection or pin 19 extending through longitudinal slot 20 on the sleeve 13 and projects into the spiral slot 18. Therefore, by relative turning movement between the sleeve 13 and sleeve 16, this projection is carried by the slot 20 along the inclined walls of the spiral slot 18, feeding the carrier 11 and the plastic strip 12 mounted therein longitudinally of the body shell or casing 10. At its upper end the slot 20 is preferably provided with a short lateral extension 21, so that as the projection 19 reaches the upper end of the slot 20 it will move into this offset and lock the carrier 11 and stick 12 in the projected position for use, so that pressure on the end of the stick in applying the material to a surface will not force the stick inwardly. The outer body shell is preferably provided with an inturned upper end or flange 22 over the outer end of the inner sleeve 13 to improve the appearance and protect the ends of the inner sleeve.

The inner sleeve 13 is operated by an end cap or finger grip 23 secured to the lower end of the sleeve 13. It may be secured to the sleeve in various ways, but that shown is to provide the member 20 with a socket 24 into which the lower end of the sleeve 13 is forced with a tight or press fit to secure the two together so that rotation of the member 23 will also rotate the sleeve 13 to operate the propeller mechanism for the stick 12; or if the member 23 is held stationary, rotation of the outer body member 10 will have the same effect. Therefore, the propeller mechanism is operated by relative rotation between the members 10 and 23.

When not in use, the entire outer shell or body casing 10 and enclosed parts is covered and enclosed in a removable closure cap or cover 25 telescoped over the casing 10, but leaving the finger grip or end cap 23 exposed. The cover 25 is of slightly greater internal diameter than the external diameter of the outer member 10, so that there is a slight clearance 26 between them, and the cover 25 is free to turn relative to the member 10 and the finger grip 23 without turning either of these members. Means is provided for releasably retaining the closure cap or cover 25 in this position, that shown in Fig. 1 comprising a ring 27 located between the lower end 28 of the outer body member 10 and the top end wall 29 of the end cap or finger grip 23. This ring is mounted with a slight clearance between these members and also the inner sleeve 13, so that it is a freely rotatable ring, and it may retain the cover 25 with a tight frictional telescopic fit with the lower end of the member 25 so that the member may be forced over this

ring in closing the device, but the fit should be of a type to permit removal of the closure 25 for use. It is, however, preferred to provide a somewhat more positive retaining means for the closure 25 on the ring 27, such, for example, as a shallow peripheral groove 30 in the outer wall of the ring 27, and then provide the closure 25 with one or more inwardly projecting small bumps 31 adapted to seat in this groove and retain the cover in place on the ring. There is ordinarily enough spring action between the closure cap and the ring to permit these bumps to slide over the outer surface of the ring to and from the groove in applying or removing the cover 25, but, if preferred, the cover may be slit on one or both sides of the bumps so that they are on spring lugs. The ring 27 is of a slightly greater outer diameter than the outside diameter of the casing 10 so as to keep the cover or cap 25 slightly spaced from the casing. With this construction, when the cap or closure 25 is in place, as shown in Fig. 1, it encloses the body shell 10 and the parts closed within this body, but is free to turn relative to this member 10 and the finger grip 23, so that any rotation of the finger grip 23 while holding the closure cap 25 stationary, would merely cause the outer body member 10 and the elements enclosed therein to rotate with the member 23, and therefore will not cause relative rotation between the member 10 and the member 23 to operate the propeller means for the stick 12, and therefore it would be impossible to operate this mechanism to jam this stick against the outer closed end 32 of the closure 25. Similarly, if the member 23 is held stationary and the cover or closure 25 is rotated, the propeller mechanism will not be operated for the same reason.

As previously suggested, the lower bead 15 of the inner body sleeve 13 is preferably located as low as possible to permit the use of a longer sleeve 16 and greater travel to the carrier 11. For this reason it is preferred to locate this bead at the lower end of the member 10 and just above the ring 27 as shown, but it can be located higher if preferred. When located at the lower end of the member 10 it will assist the member 10 in holding the ring 27 against upward longitudinal movement, but the lower end of the member 10 is relied upon primarily for holding the ring 27 in position in combination with the upper end wall of the cap 23. With this arrangement the ring 27 when the closure 25 is in position is entirely enclosed within this closure, and the lower end 33 of the member 25 is closely adjacent the top wall 29 of the end cap or finger grip 23. Therefore, the only break apparent in the device is the line between the ends of the members 25 and 23, giving a very neat and attractive appearance, and there is nothing to catch on other objects in the handbag or other carrying means.

In Figs. 5 to 8 are shown various modifications of means for mounting the freely rotating cover retaining ring corresponding to the ring 27. In Fig. 5 the ring 34 is somewhat wider than the ring 27, so that the lower portion of this ring extends into an annular recess 35 formed in the end cap or finger grip 36 corresponding to the cap 23. This cap is secured to the inner operating sleeve 13 for operating it to propel and retract the cosmetic stick 12, the same as described in connection with Fig. 1. The ring 34 is provided with an annular groove 37 in its outer wall above the end wall 38 of the member 36

into which the bumps 31 of the closure cap 25 snap and are seated to retain the cap 25 in position. The ring 34, however, is a freely rotatable ring, but is held against longitudinal movement by the lower end of the body shell 10 and the upper wall 39 of the member 36, and which is really the bottom wall of the recess 35, this being formed by extending the outer portion of the member 36 upwardly, as shown at 40. With this arrangement, the lower portion of the ring is enclosed by this upward extension of the cap 36, providing a further guiding and protecting means for the ring 34, and when the cap 25 is removed, the lower end of the ring is enclosed, giving a better appearance and preventing entrance of dirt between the ring and the cap 36.

In Fig. 6, the freely rotatable ring 41 is mounted between the lower end 28 of the body shell 10 and the top wall 42 of the end cap of finger grip 43, but the ring is also wider than the ring 27 and is provided with an annular groove 44 in its inner wall to receive a series of outwardly extending bumps 45 formed on the outer surface of the inner sleeve 13, so that this groove and these bumps assist in retaining the ring 41 in position. The closure cap or cover 25 is provided with the inwardly projecting bumps 31 on its inner side to seat in a groove 46 in the outer surface of the ring to retain the cap on this ring, the same as in the other forms, although the lower end portion of the cap 25 is preferably extended sufficiently to entirely enclose the ring 41.

In Fig. 7, the freely rotatable ring 27 is practically the same as that of Fig. 1, but in this form an additional retaining means on the lower end 28 of the outer body shell or casing 10 is provided by reducing the lower end portion 47 of the inner sleeve 13 to form a shoulder 48 overlapping the inner portion of the ring 27, this reduced end portion 47 being mounted in the end cap or finger grip 49 the same as in the other forms. In this form there is sufficient clearance between the ring 27, the end 28, shoulder 48, end portion 44 and top wall 50 of the cap 49 so that it is a freely rotating ring and retains the closure cap or cover 25 for free rotation relative to the outer shell or body 10 and the end cap or finger grip 49, the same as in the other forms.

In Fig. 8 the end cap or finger grip 51 is provided with a reduced upward extension 52 embracing the end of the inner sleeve 13, and the freely rotatable ring 53 corresponding to the ring 27 and the other rings embraces this extension 52, but with a slight clearance so that it is freely rotatable thereon. It may be retained by an annular groove 54 on the inner side of the ring into which outwardly extending bumps 55 on the lower end portion of the sleeve 13 project. This ring is also held between the lower end 28 of the closure cap or cover 25 and the top wall 56 of the end cap or finger grip 51, the same as in the other forms, and the cap 25 is retained by this ring by the nubs or projections 31 snapping into and seating in an annular groove 57 in the outer wall of the ring.

It will be clear from the above that in each of the forms shown the freely rotatable ring for retaining the closure cap or cover 25 in place telescoped over the outer shell or body casing 10, is in all forms located and retained between the lower end 28 of the member 10 and the end cap or finger grip secured to the end of the inner operating sleeve 13 for operating this sleeve. Also, in all forms the lower end of the closure

cap 25 encloses the exposed portion of this rotatable ring when the closure cap is in place, so that in all forms the only break in the outer surface of the article is the fine line between the end 33 of the cap 25 and the top or end wall of the end cap or finger grip 23, 36, 43, 49, or 51, as the case may be. Further, in all forms the retaining ring is of a somewhat larger outside diameter than the outer diameter of the casing 10 so as to space the closure cap 25 a short distance from the casing. Also, in all cases, as the ring is a free floating or freely rotatable ring the closure cap or cover 25 is always free to turn relative to the outer body shell 10 and the lower end cap or finger grip. Therefore, when the cap 25 is in place it is impossible to operate the propeller mechanism for the plastic stick 12 to project this stick and jam or crush its outer end against the closed end 32 of this closure 25.

Having thus set forth the nature of my invention, what I claim is:

1. A holder of the character described comprising a casing open at one end, a carrier for a stick of plastic or the like movable longitudinally in the casing, a rotatable finger grip at the other end of the casing, means operated by relative turning movement between the finger grip and casing for shifting the carrier, said finger grip being provided with a lateral shoulder spaced from the inner end of the casing, a ring mounted between the end of the casing and said shoulder and free to turn relative thereto, said ring having an external diameter somewhat greater than and an internal diameter less than the outer diameter of the casing, a closure cap telescoped over the casing from its open end and of greater internal diameter than the external diameter of the casing for free turning movement relative thereto, said cap being telescoped at its inner end over the ring, and cooperating means on the ring and cap to releasably retain the cap in position enclosing the casing.

2. A holder of the character described comprising a casing open at one end, a carrier for a stick of plastic or the like movable longitudinally in the casing, a rotatable finger grip at the other end of the casing, means operated by relative turning movement between the finger grip and casing for shifting the carrier, a closure cap telescoped over the casing from its open end and having an internal diameter somewhat greater than the external diameter of the casing for free turning movement relative to the casing, said finger grip including a lateral shoulder spaced from the inner end of the casing, a retaining ring mounted between the end of the casing and said shoulder and free to turn relative thereto, said ring being of somewhat greater external diameter than and of less internal diameter than the external diameter of the casing and provided with an annular groove, and the inner end of the cap being telescoped with the ring and provided with lateral projections extending into said groove to detachably retain the cap in position enclosing the casing.

3. A holder of the character described comprising a casing open at one end, a carrier for a stick of plastic or the like movable longitudinally in the casing, a rotatable operating sleeve in the casing, means operated by relative turning movement between the sleeve and casing for shifting the carrier, an enlarged head on the sleeve at the other end of the casing forming a finger grip for operating the sleeve, said head being spaced from the inner end of the casing, a retaining ring

mounted between the inner end of the casing and the head and free to turn relative thereto, said ring having an external diameter somewhat greater than and an internal diameter less than the external diameter of the casing, a closure cap telescoped over the casing from its open end and of somewhat greater internal diameter than the external diameter of the casing for free turning movement relative thereto, and means for releasably connecting the inner end of the cap with the ring to retain the cap in position enclosing the casing.

4. A holder of the character described comprising a casing open at one end, a carrier for a stick of plastic or the like movable longitudinally in the casing, a rotatable operating sleeve in the casing, means operated by relative turning movement between the sleeve and casing for shifting the carrier, an enlarged head on the sleeve at the other end of the casing forming a finger grip for operating the sleeve, said head being spaced from the inner end of the casing, a retaining ring mounted between the inner end of the casing and the head and free to turn relative thereto, said ring being of somewhat greater external diameter than and of less internal diameter than the external diameter of the casing and provided with an annular groove in its outer side wall, a closure cap telescoped over the casing from its open end of somewhat greater internal diameter than the external diameter of the casing for free turning movement relative thereto, the inner end of the cap being telescoped over the ring and provided with inward projections seated in the groove to retain the cap in position thereon enclosing the casing, said projections being yieldably mounted to pass over the ring to and from the groove.

5. A holder of the character described comprising a casing open at one end, a carrier for a stick of plastic or the like movable longitudinally in the casing, a rotatable operating sleeve in the casing, an intermediate stationary sleeve between the first sleeve and the casing, cooperating means on the sleeves operated by relative turning movement between the first sleeve and the casing for shifting the carrier, outwardly extending projecting means on the first sleeve at the ends of the intermediate sleeve to relatively position the sleeves, an enlarged head on the first sleeve at the inner end of the casing forming a finger grip and provided with a lateral shoulder spaced from the end of the casing, a ring mounted between the end of the casing and said shoulder and free to turn relative thereto, said ring having an outer diameter somewhat greater than and an internal diameter less than the external diameter of the casing, a closure cap telescoped over the casing from its open end and of somewhat greater internal diameter than the external diameter of the casing for free turning movement relative thereto, said cap being telescoped over the ring, and cooperating means on the ring and cap to detachably secure the cap on the ring in position enclosing the casing.

6. A holder of the character described comprising a casing open at one end, a carrier for a stick of plastic or the like movable longitudinally in the casing, a rotatable operating sleeve in the casing, means operated by relative turning movement between the sleeve and casing for shifting the carrier, an enlarged head forming a finger grip and comprising a member provided with a socket in which the inner end of the first sleeve is seated to secure the head to the sleeve, said head being provided with a lateral shoulder longitudinally spaced from the inner end of the

casing, a retaining ring mounted between said shoulder and the end of the casing and free to turn relative thereto, said ring having an outer diameter somewhat greater than the outer diameter of the casing and an inner diameter less than the outside diameter of the casing, a closure cap telescoped over the casing from its open end and of somewhat greater internal diameter than the external diameter of the casing for free turning movement thereon, said cap being telescoped at its inner end over the ring, and means to detachably retain the cap on the ring.

7. A holder of the character described comprising a casing open at one end, a carrier for a stick of plastic or the like movable longitudinally in the casing, a rotatable operating sleeve in the casing, means operated by relative turning movement between the sleeve and casing for shifting the carrier, an enlarged head on the sleeve at the other end of the casing forming a finger grip for operating the sleeve, said head being provided with a lateral shoulder spaced longitudinally from the inner end of the casing, a retaining ring mounted between the end of the casing and the shoulder and free to turn relative thereto, said ring having an outer diameter somewhat greater than and an inner diameter less than the outer diameter of the casing, said ring being provided with an annular groove in its outer surface, a closure cap telescoped over the casing from its open end and of somewhat greater internal diameter than the external diameter of the casing for free turning movement thereon, and said cap being telescoped over the ring at its inner end and provided with yieldable projections seated in said groove to releasably retain the cap in position enclosing the casing.

8. A holder of the character described comprising a casing open at one end, a carrier for a stick of plastic or the like movable longitudinally in the casing, a rotatable operating sleeve in the casing, means operated by relative turning movement between the sleeve and casing for shifting the carrier, an enlarged head on the sleeve at the other end of the casing forming a finger grip for operating the sleeve, said head being spaced from the inner end of the casing and provided with an annular recess opposite the end of the casing, a retaining ring mounted between the head and the lower end of the casing and free to turn relative thereto, said ring located with its lower portion enclosed in said recess, said ring being of an external diameter slightly greater than and an internal diameter less than the external diameter of the casing and provided with an annular groove in its outer wall, a closure cap telescoped over the casing from its open end and of slightly greater internal diameter than the external diameter of the casing for free turning movement thereon, and the inner end of the cap being telescoped over the ring and provided with projections seated in said groove to retain the cap in position enclosing the casing and adapted to yield to permit application and removal of the cap.

9. A holder of the character described comprising a casing open at one end, a carrier for a stick of plastic or the like movable longitudinally in the casing, a rotatable operating sleeve in the casing, means operated by relative turning movement between the sleeve and casing for shifting the carrier, an enlarged head on the sleeve at the other end of the casing forming a finger grip for operating the sleeve, said head being provided with a lateral shoulder spaced longitudinally from the end of the casing, said sleeve being pro-

vided with an outwardly extending shoulder adjacent the end of the casing, a retaining ring mounted between the shoulders and free to turn relative thereto, said ring having an outer diameter somewhat greater than and an inner diameter less than the outer diameter of the casing, a closure cap telescoped over the casing from its open end and having an internal diameter somewhat greater than the external diameter of the casing for free turning movement relative to the casing, said cap being telescoped at its inner end over the ring, and cooperating means on the ring and cap to detachably secure the cap in position enclosing the casing.

10. A holder of the character described comprising a casing open at one end, a carrier for a stick of plastic or the like movable longitudinally in the casing, a rotatable operating sleeve in the casing, means operated by relative turning movement between the sleeve and casing for shifting the carrier, an enlarged head on the sleeve at the other end of the casing forming a finger grip for operating the sleeve, said head being provided with a lateral shoulder spaced longitudinally from the end of the casing and a tubular extension embracing the sleeve and extending toward the casing, a retaining ring mounted on said tubular extension and free to turn relative thereto, said ring being of an external diameter somewhat greater than and an internal diameter less than the external diameter of the casing, means to retain the ring on the extension, a closure cap telescoped over the casing from its open end and having an internal diameter somewhat greater than the external diameter of the casing for free turning movement relative to the casing, said cap being telescoped at its inner end over the ring, and cooperating means on the ring and cap to releasably retain the cap in position enclosing the casing.

11. A holder of the character described comprising a casing open at one end, a carrier for a stick of plastic or the like movable longitudinally in the casing, a rotatable finger grip at the other end of the casing, means operated by relative turning movement between the finger grip and casing for shifting the carrier, said finger grip being provided with a lateral shoulder spaced from the inner end of the casing, a ring mounted between the end of the casing and said shoulder and free to turn relative thereto, said ring having an external diameter somewhat greater than and an internal diameter less than the outer diameter of the casing, a closure cap telescoped over the casing from its open end and of greater internal diameter than the external diameter of the casing for free turning movement relative thereto, said cap being telescoped at its inner end over the ring, means releasably retaining the ring and the inner end of the cap together for unit rotation.
